UNITED STATES PATENT OFFICE

CHARLES P. STEINMETZ, OF SCHENECTADY, NEW YORK, ASSIGNOR TO GENERAL ELECTRIC COMPANY, A CORPORATION OF NEW YORK.

TURBINE.

No. 872,545.

Specification of Letters Patent.

Patented Dec. 3, 1907.

Application filed June 10, 1907. No. 378,083.

To all whom it may concern:

Be it known that I, CHARLES P. STEINMETZ, a citizen of the United States, residing at Schenectady, county of Schenectady, State of New York, have invented certain new and useful Improvements in Turbines, of which the following is a specification:

In any elastic fluid turbine comprising bucket wheels located in a containing casing 10 with diaphragms between, there is always leakage through the shaft clearances between the stages or wheel compartments even though packings are provided. This leakage means a loss to the stage from which 15 it takes place. In such a turbine there is a certain amount of loss due to the fact that the wheels are rotating in a fluid body containing more or less moisture. Other things being equal the greater the moisture of the 20 steam or other fluid body in which the wheels rotate the greater the rotation loss.

The object of my invention is to improve the efficiency of elastic fluid turbines of the type above referred to by decreasing the rotation losses. More specifically, I utilize the 25 leakage fluid from stage to stage to perform useful work by causing it to maintain a body of dry or superheated fluid at the sides of the rotating wheels and therefore decrease the 30 resistance to rotation.

In carrying out my invention in one of its simplest forms a casing is provided in which the bucket wheels rotate with suitable separators between. In the specific embodiment 35 of the invention the casing is divided by diaphragms into wheel compartments or stages, each containing a wheel having one, two or more rows of buckets. Carried by the diaphragms and closely surrounding the shaft 40 or the wheel hubs as the case may be are packing sleeves. Between the sleeves and the rotating members are of necessity small clearances to prevent the parts from seizing. It is to be noted in this connection that the 45 packing sleeves have to be so located that they are not readily accessible for the purpose of adjustment.

Situated in close proximity to both sides of the wheels but separated by small auxiliary chambers are walls which closely conform to the shape of the wheel webs and may also to the whole wheel. These walls may form a part of the diaphragm and casing structure but preferably on account of de- 50 creased cost of manufacture and the reduc-

tion in weight, especially in large machines, are made of relatively thin sheet metal plates. Into the auxiliary chambers thus formed the leakage from one stage packing to another passes and by reason of the drop in pressure, 60 the steam is superheated or at least made dry. The plates also serve to prevent the motive fluid exhausting from the bucket wheels from reacting on the wheel and opposing its rotation. I prefer to make these 65 chambers as small as possible consistent with the free running of the wheel and at the same time large enough to pass the steam leaking through the clearances. The space between the wheel and the plates or walls will generally be somewhat longer in a large machine 70 than in a small machine. After the steam passes through the auxiliary chambers on the sides of the wheels it passes to the main wheel chambers and thence to the stage nozzles or exhaust as the case may be. In the 75 first stage I may admit steam to the chambers at the pressure of admission and therefore prior to its passing through any of the nozzles or other discharging devices. In order that the steam may act equally or substantially so on both sides of the wheels the webs thereof are provided with one, two or more openings or passages through which the 80 leakage steam passes to insure a body of dry 85 or superheated steam on both sides of the wheel webs. In addition to the auxiliary chambers referred to, are main chambers that receive the steam exhausting from the wheel buckets and after equalizing the pressure of the several streams, discharge it with the steam from the auxiliary chambers to the nozzles or other fluid discharging devices 90 leading to the next stage, or to any succeeding stage.

I may utilize my invention in connection with multi-stage turbines having a single casing divided by diaphragms or in a turbine having separate casings for the stages. In some instances it will be found desirable to 100 use my invention in connection with machines having only a single stage.

In the accompanying drawing, which illustrates one of the embodiments of my invention, is shown a longitudinal section of a 105 multi-stage turbine.

1 indicates the casing, which is provided with a head 2 and a base, not shown. Formed on the inside of the casing are shoulders 3 for supporting the diaphragms 4, the 110

- latter dividing the casing into wheel compartments or stages. The bucket wheels 5 are mounted upon the upright shaft 6. Each bucket wheel is provided with two rows of 5 buckets 7, between which are more or less complete rows of intermediate buckets 8. Located above the first stage wheel is an annular plate 9, conforming in shape to the wheel-web and the buckets attached thereto. 10 It is provided with a hub-like extension 10, which makes a close fit with the annular bore of the head 2. Situated above the extension 10 and surrounding the main shaft is a packing 11 to prevent the escape of steam from 15 the first wheel compartment to the atmosphere, or the entrance of air to the first stage when the latter is working at a pressure below the atmosphere. The plate 9 is supported at the outer end by a series of projections 12 formed on the head 2. Owing to 20 the fact that these projections are not continuous, steam in the main compartment or chamber 13 has access to the space above it. Situated below the wheel is an annular plate 25 14 that conforms in shape to that of the wheel-web and the buckets affixed thereto. This plate is supported by a series of small projections 15 at a point near the shaft, and by a series of projections 16 at a point near 30 the periphery. Steam from the chamber 13 has access to the space below the plate. Since the spaces above and below the plates 9 and 14 are in free communication with the annular chamber 13 they all constitute in effect one chamber. Mounted in the upper diaphragm is a packing sleeve 17 that is free to move in a plane perpendicular to the shaft, for the purpose of adjustment. It is held in place by a ring 18 located above it. The 35 packing sleeve 17 is so arranged that it projects into the cylindrical portion of the upper plate 9 of the second stage, and since the cylindrical extension 10 of the plate makes a close fit with the bore of the diaphragm, it follows that any steam leaking through the clearance will pass to the auxiliary chamber 19, which is formed by the stationary plate and the revolving wheel. In order to equalize the pressures on the opposite sides of the 40 wheel, and to permit the super-heated or dry steam leaking from the packing to act on both sides of the wheel, passages 20 are provided that extend through the wheel-web. The position of these passages is immaterial, 45 so long as the above effect is obtained. The construction and arrangement of the plates and the wheels in the succeeding stages are the same, and hence, further description is unnecessary.
- 50 In the event of it being desirable to supply fluid to the auxiliary chamber 19 on the upper side of the first stage-wheel at a temperature above that in the main chamber 13, a pipe 21 is provided, containing a throttle-valve 22, which connects the valve-chest 23 with the annular space communicating with the auxiliary chamber 19.
- Steam is admitted to the turbine by valves in the chest 23 and passes through the nozzles 24 to the first wheel. After exhausting 70 from the wheel the steam enters the annular chamber 13 and flows through the second stage nozzles, where the action is repeated, the steam finally passing by the exhaust conduit either to the atmosphere or to a condenser. 75
- I have described my invention in connection with a vertical-shaft turbine of the Curtis type, but it is to be understood that the invention is capable of wider application. 80
- In accordance with the provisions of the patent statutes, I have described the principle of operation of my invention, together with the apparatus which I now consider to represent the best embodiment thereof; but 85 I desire to have it understood that the apparatus shown is only illustrative and that the invention can be carried out by other means.
- What I claim as new, and desire to secure by Letters Patent of the United States, is, — 90
1. In an elastic fluid turbine, the combination of a bucket wheel, a casing therefor containing a main chamber for the wheel, admission and exhaust conduits, stationary walls located adjacent to the sides of the 95 wheel, and means for introducing fluid into the auxiliary chambers formed between the wheel and the walls at a temperature above that of the fluid passing through the wheel buckets to reduce the rotation losses. 100
  2. In an elastic fluid turbine, the combination of a bucket wheel, a casing therefor containing a main chamber for the wheel, admission and exhaust conduits, stationary walls located adjacent to the sides of the 105 wheel, means for introducing fluid into the auxiliary chambers formed between the wheel and the walls at a temperature above that of the fluid passing through the wheel buckets to reduce the rotation losses, and a 110 passage which connects the auxiliary chambers. 110
  3. In an elastic fluid turbine, the combination of a bucket wheel, a casing therefor containing a main chamber for the wheel, admission 115 and exhaust conduits, a plate located on one side of the wheel and carried by the casing to form an auxiliary chamber independent of the main wheel chamber, and a means for introducing a fluid into the auxiliary chamber whose temperature is above that of the fluid passing through the buckets and contained in the main chamber for the purpose of reducing rotation losses. 120
  4. In an elastic fluid turbine, the combination of a casing, a diaphragm dividing the casing into main wheel chambers, bucket wheels mounted therein, walls situated on both sides of the wheels approximately conforming in shape thereto to form auxiliary 125 130

- chambers that are independent of the main wheel chambers, a packing between the diaphragm and the rotating member of the machine, which is so arranged that the leakage 5 therefrom passes to the auxiliary chamber to reduce rotation losses, and admission and exhaust conduits.
5. In an elastic fluid turbine, the combination of a casing, diaphragms dividing the 10 casing into main wheel chambers, buckets wheels mounted therein, plates mounted in the chambers and situated on opposite sides of the wheels and separated therefrom by small auxiliary chambers, passages in the wheels connecting the auxiliary chambers on 15 opposite sides thereof, and packing sleeves carried by the diaphragms, the leakage from which passes through the auxiliary chambers to reduce rotation losses and thence passes to the main chambers. 20

In witness whereof, I have hereunto set my hand this 8th day of June, 1907.

CHARLES P. STEINMETZ.
